WILLIAM LAWRENCE
Chadwick, N.Y. Atty.

UNITED STATES PATENT OFFICE.

WILLIAM LAWRENCE, OF CHICAGO, ILLINOIS.

VENTILATING DEVICE.

Application filed February 13, 1922. Serial No. 536,000.

To all whom it may concern:

Be it known that I, WILLIAM LAWRENCE, a citizen of the United States, and a resident of the city of Chicago, in the county 5 of Cook and State of Illinois, have invented certain new and useful Improvements in a Ventilating Device; and I do hereby declare that the following is a full, clear, and exact description of the same, reference being had 10 to the accompanying drawings, and to the numerals of reference marked thereon, which form a part of this specification.

This invention relates to a ventilating device for dwelling rooms or the like, and 15 it is an object of this invention to provide a ventilator equipped with cutting or boring elements whereby the device may be readily attached in a wall or the like.

It is a further object of this invention 20 to equip the same with a sensitive fan that is responsive to ordinary air currents whereby a forced ventilation is secured.

With these and other objects in view, which will become more apparent in the following description and disclosures, this invention comprises the novel mechanisms and combinations hereinafter described and more particularly pointed out and defined 25 in the appended claim.

30 In the accompanying drawings, which illustrate a preferred embodiment of this invention, and in which similar reference numerals refer to similar features in the different views:

35 Figure 1 is a vertical section through the improved ventilating device.

Figure 2 is a section through a wall or ceiling showing the ventilating device in elevation.

40 Figure 3 is a bottom plan view of the device.

Figure 4 is a top plan view of the ventilating fan.

45 Figure 5 is a fragmentary section through the device illustrating a one-way yielding stop for the fan that may be employed.

As shown on the drawings:

50 In referring now to the drawings, which illustrate one embodiment of this invention, the numeral 1 represents a hollow cylindrical member provided with a hollow cylindrical extension 2 communicating with the interior of said member and in which there 55 are a plurality of slots or ventilating vents

3. The end of the extension is closed by a metal head 4 which forms a support for a cutting or boring element in the form of a centering bit 5 which may be attached thereto in any well-known way. In the present 60 instance, depressions are formed in the upper surface of the head 4 into which tongues or lugs 6 stamped from the base of the cutting element project to prevent relative rotation between the head and cutting element, the cutting element being anchored to the head by its pointed centering element 7 which is separately formed and provided with a reduced threaded shank screwing centrally into the head 4.

70 The centering bit or cutting element 5 is adapted for making a hole in the wall or ceiling and through the lath thereof. And in order to securely retain the extension 2 in the hole thuswise formed, said extension 75 is externally screw threaded, the upper portion of said extension being slightly reduced and the screw threads on said reduced portion merging into the screw threads on the lower or enlarged portion, 80 whereby the upper screw threads will start a thread in the wall of the hole to be deepened and completed by the threads on the enlarged portion whereby the enlarged portion 85 will be retained by a binding effect produced by enlarging the hole cut by the centering bit.

A cap 8 having a plurality of ventilating vents or apertures 9 is screw threaded into the outer end of the cylindrical member 1, 90 and a shutter 10 provided with an operating handle 11 is superimposed upon the upper or inner side of the cap 8 and is rotatably adjustable for opening or closing said vents.

95 A jewel bearing 12 is secured centrally of the cap 8 and extends upwardly into the hollow cylindrical member 1 for rotatably supporting a highly sensitive circular fan 13 having inclined vanes or blades 14 which 100 are adapted to be acted upon by air currents for rotating the fan whereby the fan might be said to be responsive to air currents.

105 In order that the fan 13 will be prevented from rotating in the wrong direction for emitting currents of air from the room, a slender hair spring 15 or the like may be secured upon the upper wall of the cylindrical member and bent downwardly to engage 110

the blades of the fan against reverse rotation, the spring flexing over the blades for direct rotation of the fan.

This ventilating device is adapted to be secured in a wall or ceiling 16 backed by laths 17, as illustrated in Figure 2, the hollow ventilating extension extending into the hollow space between the walls of the room or between the ceiling and floor above, through which currents of air are generally circulating.

From the foregoing description, it will be apparent that I have invented a novel form of ventilator for a dwelling that is designed to bore its own securing aperture in the wall, that is equipped with a highly sensitive fan responsive to air currents to produce rotation thereof for forcing a draft of air from the room.

I am aware that numerous details of construction may be varied through a wide range without departing from the principles of this invention, and I therefore do not purpose limiting the patent granted otherwise than necessitated by the prior art. 20 25

I claim as my invention:

In a device of the class described a ventilator comprising a hollow cylindrical member, a cap member threaded in said hollow cylindrical member, said cap having vents, a bearing pin supported by said cap, a shutter rotatable on said pin for closing said vents, said pin extending through said shutter, and a sensitive fan rotatably mounted on said pin. 30 35

In testimony whereof I have hereunto subscribed my name.

WILLIAM LAWRENCE.
